UNITED STATES PATENT OFFICE

PHILIPP VANNINI, OF ZUG, SWITZERLAND, ASSIGNOR TO LANDIS & GYR, A.-G., A LIMITED JOINT STOCK COMPANY OF SWITZERLAND

SWITCH ACTUATING MECHANISM

Application filed August 14, 1929, Serial No. 385,744, and in Switzerland August 23, 1928.

This invention relates to a new and useful switch actuating mechanism and more particularly to such a mechanism particularly adapted to form a part of a time controlled switch.

Objects and advantages of the invention will be set forth in part hereinafter and in part will be obvious herefrom, or may be learned by practice with the invention, 10 the same being realized and attained by means of the instrumentalities and combinations pointed out in the appended claims.

The invention consists in the novel parts, construction, arrangements, combinations 15 and improvements herein shown and described.

The accompanying drawing, referred to herein and constituting a part hereof, illustrates one embodiment of the invention, and 20 together with the description, serves to explain the principles of the invention.

Of the drawing:—

Fig. 1 is a fragmentary elevation of one embodiment of my invention;

25 Fig. 2 is a vertical section taken on the line 2—2 of Fig. 1;

Fig. 3 is an elevation of a modified form of actuating member; and

30 Fig. 4 is a plan of the embodiment shown in Fig. 3.

In the usual construction of time-controlled switches, the clock-driven disc is provided with a plurality of threaded switch-actuating pins, threadedly secured around the periphery of the disc, and this construction necessitates the provision of a very large number of relatively small tapped holes around the periphery of the disc. Such a construction is expensive and does not lend 35 itself readily to quantity production, and also necessitates a relatively large spacing between adjacent holes.

The present invention provides a switch 40 actuating mechanism of the class described which can be made accurately in large quantities at a relatively low price, at the same time facilitating the adjustment of the switch-actuating members so that the time of operation of the switch can be more easily 45 changed.

According to the present preferred embodiment of the invention, there is provided a toothed disc, which may be driven by suitable clock-mechanism, on which the switch-actuating members are mounted. These 55 switch-actuating members are preferably formed slightly longer than the thickness of the disc, and are provided with depending resilient fingers to engage and press against the sides of the disc. Preferably, and as here 60 shown, the switch-actuating members are adapted to be fitted into the recesses formed by the space between pairs of adjacent teeth, and, if desired, there may be provided a shallow groove on one or both sides of the 65 disc and concentric therewith, into which may project a small projection on the inside of one or both of the fingers, to securely hold the switch-actuating members against inadvertent displacement. 70

Referring now in detail to the accompanying drawing illustrating the present preferred embodiment of the invention, there is provided a switch, which may be of any convenient form, but is here shown as formed of a pair of contacts 10, 11 mounted on conducting springs 12, 13 supported by insulating block 14, which contacts may control any desired circuit, such as the bell circuit shown. For closing the switch, by pressing contacts 10, and 11 together, there is provided a pin 15, mounted on lever 16, pivoted on insulating block 14 by means of pivot pin 17, lever 16 80 being actuated by means of the clock-driven mechanism about to be described.

For actuating the switch closing lever at predetermined and variable times there are 85 preferably provided switch actuating members variably positionable on clock-driven toothed disc 18, rotatably mounted on shaft 18a driven by pinion 19, which in turn is driven by any suitable form of clock-mechanism. In order to permit the disc 18 to be driven directly by the clock-mechanism, 90 the teeth 20 of the disc 18 are preferably formed considerably deeper than the usual form of gear teeth, and between pairs of adjacent teeth are secured the switch-actuating members 21, substantially filling the 95 100

inner portion of the space between a pair of adjacent teeth.

Switch-actuating members 21 are preferably formed of a bar 22 having a rounded upper surface and are slightly longer than the thickness of the disc 18 so as to project on each side of the disc, and contact with the downwardly extending portion 23 at the end of lever 16, as the members 21 are moved 10 past the lever. For securely holding the switch-actuating members in the desired position, and at the same time allowing their ready removal when it is desired to vary the time of actuation of the switch, the actuating members are preferably provided with radial, inwardly-extending, slightly resilient fingers 24 each of which may be provided with an inwardly extending boss 25 to engage the sides of the disc 18 and securely hold the 20 actuating members. The space between the bosses 25 is preferably slightly less than the thickness of the disc, causing the fingers to be sprung slightly as the actuating members are pushed in place.

When it is desired to hold the actuating members 23 more securely in position, there may be provided a groove 25', on one or both sides of the disc 18 concentric with the disc, and closely adjacent to the peripheral teeth 20 of the disc to receive the corresponding boss. By reason of the rounded surface of the bosses, the actuating members may be positioned or removed by simple radial movement.

If desired, and as shown in Figure 2, two switches may be actuated by the same actuating member, by arranging the corresponding switch actuating lever on opposite sides of the disc.

For actuating only one of the switches one of the portions 26 of the actuating member overhanging the side of disc may be omitted, and for actuating the switch at a time other than that permitted by the position of the teeth 20, this overhanging portion 26 may be offset to a greater or less extent, as shown in Figure 4. Thus, if the teeth are separated by five minute intervals, there may be provided one actuating member 21 like that shown in Figures 1 and 2, and four others, offset to a greater or less extent, as shown in Figure 3, thereby allowing the switch to be actuated at one minute intervals by proper selection of the actuating member and the proper recess 50 in the periphery of the disc 18.

The invention in its broader aspects is not limited to the specific mechanisms shown and described but departures may be made therefrom within the scope of the accompanying 60 claims without departing from the principles of the invention and without sacrificing its chief advantages.

What I claim is:—

1. Switch actuating mechanism for time-controlled switches and the like including

in combination a driven disc having a plurality of symmetrically arranged clip-receiving, peripheral recesses and a switch-actuating clip fitting within the recess and engaging the sides of the disc.

70

2. Switch actuating mechanism for time-controlled switches and the like including in combination a driven disc having a plurality of peripheral recesses, a groove concentric with the disc and adjacent to the recesses and a switch-actuating clip adapted to fit in the recesses and engage the groove.

75

3. Switch actuating mechanism for time-controlled switches and the like including in combination a toothed clock driven disc, a switch-actuating member positioned between a pair of adjacent teeth and having depending yielding fingers engaging the sides of the disc.

80

4. Switch actuating mechanism for time-controlled switches and the like including in combination a toothed clock driven disc, a groove concentric with the disc, a switch-actuating member positioned between a pair of adjacent teeth and having depending yielding fingers engaging the sides of the disc and the groove.

85

5. Switch actuating mechanism for time controlled switches and the like including in combination a clock-driven disc, a groove concentric with the disc and a switch-actuating member carried on the periphery of said disc and having a pair of resilient fingers pressed against the sides of the disc, one of said fingers being provided with an inwardly extending projection to engage said groove and securely position the member.

90

In testimony whereof, I have signed my name to this specification.

PHILIPP VANNINI.
